UNITED STATES PATENT OFFICE

JOSEPH ZANG, OF ST. LOUIS, MISSOURI

CUTTING AND FLANGING TOOL

Application filed October 18, 1929. Serial No. 400,504.

This invention has for its prime object the provision of a novel and efficient tool for cutting a circular aperture in the head of metal drums, such as those used for the shipment of heavy grease or oil, and flanging the edge of such aperture so that a cap may be fitted securely therein, to the end that the interior of the receptacle may be thoroughly cleansed and rendered usable for the shipment or storage of all manner of liquids, solids or semi-solids. However, it will be obvious that use of the tool is not limited to metal drums, but that it can be employed for cutting and flanging apertures in boilers, tanks and any other cylindrical objects.

Referring to said drawings, wherein like numerals refer to like parts throughout the several views, Figure 1 is a view of the complete tool in elevation; Figure 2 is a sectional elevation of the tool; Figure 3 an additional view in elevation differing from Figure 1 in that the parts are shown in the position assumed while flanging an aperture; Figure 4 a top plan view of the upper flanging elements; and Figure 5 a top plan view of the lower flanging elements.

The operation of the tool is, preferably, effected by connection with an ordinary drill-press and in Figures 1, 2 and 3 the revoluble shaft of the press is indicated by numeral 1. The portion of said shaft adjacent to and connecting with the tool proper is enclosed by a stationary sleeve 2 and its lower extremity is provided with a tapered bore for the reception of the head of a spindle 3 secured by a key 4 which may be inserted through key-way 5. Said key, however, does not engage said sleeve which, as before stated, is at all times stationary and serves to support a socket or chuck 6 which is split lengthwise for the purpose of adjustment and secured in place by bolt 7.

The lower portion of said socket is threaded for engagement with the threads of a hub 8 carrying a hand-wheel 9, and a two-part collar 10 revolvably seated in an annular recess formed in the lower portion of said hub is connected by screws 11 with a cone-shaped block 12 as shown in Figure 2.

Plate 13 (Figure 4) is secured to block 12

by screws 14 and comprises a plurality of short extensions 13a serving as axles for the upper set of flanging rollers 15. Pivotally secured to said plate at 16 are bell-crank levers 17 which, in turn, are pivotally connected at 18 with axles 19 carrying the lower series of flanging rollers 20. By reference to Figures 3 and 5 it will be observed that axles 19 are pivotally secured at 21 within complementary recesses 22 provided in the arms 23 which, collectively, form what may be termed the "anvil" element of the tool, and said anvil, like plate 13, is mounted upon and revolves in unison with spindle 3 which is provided with ribs or keys 24.

The lower extremity of spindle 3 carries a removable toothed cutter 25 and a drill 26 for centering the incision in the head of a drum 27 (Figure 1) or similar object which is made by said cutter.

In operation, the drill 26 first perforates the head of the drum at its center and the cutter 25 then contacts with the head to form an aperture sufficiently large to permit of the thorough cleansing of the interior of the receptacle. The aperture thus provided affords passage for rollers 20 in the retracted position shown in Figure 2, and thereupon they are extended and brought to bear upon the inner surface of the head of the drum adjacent to the edge of the aperture by manual rotation of wheel 9. Thus disposed, the arms 23 supporting rollers 20 perform, substantially, the function of an anvil.

Manifestly, the extension of rollers 20 through the agency of levers 17 occurs coincident with the lowering of plate 13 carrying rollers 15, and thus it follows that the rim or margin of said aperture is gripped by both sets of rollers simultaneously. Having assumed this position, slight additional pressure is put upon rollers 15 by means of wheel 9 to depress the edge of said rim as shown in Figure 1 and the flange thus formed affords a seat for the frictional engagement of a cap or closure (not shown) when the receptacle is ready for shipment.

If and when it is desired to provide an upturned flange axles 13a are slightly lengthened and axles 19 correspondingly shortened

so as to position rollers 15 against the head of the drum exterior to the plane of rollers 20, the latter then serving to press upward the rim of the aperture formed by cutter 25: this is a mere reversal of the present relation of the parts mentioned.

What I claim as new and desire to secure by Letters-Patent is:—

1. A tool for cutting and flanging an aperture in the head of a metallic drum or barrel, comprising a cutter and means for rotating the same, a pair of pivoted axles mounted above said cutter and normally occupying an upright position and each of which axles carries a flanging roller on its outer end adapted to engage the interior surface of said head adjacent the edge of the aperture formed by said cutter, a pair of relatively stationary rollers normally spaced from said first-named
- 10 rollers for engaging the exterior surface of said head, a plurality of means for drawing one set of rollers toward the other and simultaneously straightening the axles of said first-named rollers after the latter have
- 20 passed through the aperture made by said cutter, whereby to cause the respective sets of rollers to grip the rim of said aperture, and means for revolving said rollers in unison as they are moved toward each other to cause
- 25 them to shape and flange the rim of said aperture.

2. A tool for cutting and flanging an aperture in the head of a metallic drum or barrel, comprising a rotatable spindle, a cutter mounted on the lower end thereof, rollers mounted on said spindle and adapted to engage the interior surface of said head adjacent the edge of the aperture formed by said cutter, said rollers having each a pivoted axle normally occupying an upright position, additional rollers adapted to engage the exterior surface of said head in proximity to the position of the first-mentioned rollers, a support on said spindle on which said latter
- 35 rollers are mounted, levers pivotally connecting said support and said axles, means for drawing one set of rollers toward the other after the pivotally-mounted rollers have been inserted through said aperture, whereby to
- 40 straighten said axles and cause the respective sets of rollers to grip opposite surfaces of said head at different distances from the edge of said aperture, and means for revolving said rollers in unison, as they are moved in opposite directions in contact with said head, to cause them to shape and flange the rim of said aperture.

JOSEPH ZANG.
